(57) **CLAIM**

The ornamental design for a multimedia processing device, as shown and described.

DESCRIPTION

Multimedia processing device

Figure 2.1 is a front view of a multimedia processing device showing the new design;

Figure 2.2 is a back view thereof;

Figure 2.3 is a left side view thereof;

Figure 2.4 is a right side view thereof;

Figure 2.5 is a top view thereof;

Figure 2.6 is a bottom view thereof;

Figure 2.7 is a front, top perspective view thereof;

Figure 2.8 is a back, top perspective view thereof; and

Figure 2.9 is a front, bottom perspective view thereof.

The broken lines shown in the drawings illustrate portions of the multimedia processing device that form no part of the claimed design.

1 Claim, 9 Drawing Sheets(56)
